Specification of Letters Patent.

Patented May 15, 1917.

Application filed June 27, 1913. Serial No. 776,104.

To all whom it may concern:

Be it known that we, JOHN P. HUNTER and HENRY KUENTZLER, citizens of the United States, residing at Wilkes-Barre, in the county of Luzerne and State of Pennsylvania, have invented new and useful Improvements in Carrying Mechanism, of which the following is a specification.

This invention relates to carrying mechanisms for calculating machines, and its novelty consists in the construction and adaptation of the parts as will be hereinafter pointed out.

Figure 1 is a side elevation of the frame of the machine supporting a train of mechanism embodying our invention; Fig. 2 is a similar view of the same parts when the main shaft is on its return stroke; Fig. 3 is a side elevation of the mechanism, illustrating the carrying operation; Fig. 4 is a detail of the carrying cam; Fig. 5, of its latch lever; Fig. 6 is a detail of the numeral wheel rib, and Fig. 7 is a detail of the zero restoring position of the carrying cam and numeral wheel.

In the drawings, 1 is the frame of the machine, 2 is the main shaft adapted to oscillate in suitable bearings in the frame 1 and actuated by a manually operated handle (not shown) or in any other suitable manner.

3 is a segment lever mounted on the shaft 2 and provided with a stop foot 4 adapted to engage a fixed part of the frame 1 (not shown).

Mounted on the shaft 2 is a crank 5 (Fig. 2) carrying a roller 6 which travels in a slot 7 of a lever 8, which is secured to its upper end to a rock shaft 9 arranged across the frame of the machine. Arms 10 depend from the shaft 9 and at their lower ends support a restoring rod 11. A transverse shaft 12 supported in suitable bearings in the frame 1 carries elbow levers 13, one for each denominational series, each loosely mounted on the shaft 12, and each yieldingly connected from its upper arm 14 through a draft spring 15 to the restoring rod 11. The lower and rearwardly projecting arm 16 of the elbow 13 co-operates with

the printing mechanism and forms no part of this invention.

To each arm 14 is pivoted a control bar or drive member 17 which extends forwardly in the frame and the movement of which in that direction is limited by stops 32 in the same manner as the rack bars in the former styles of this machine shown and described in Letters Patent of the United States Nos. 745,539 and 797,032, granted to Charles Wales.

Each bar 17 has a depending projection 18^a which is adapted to be engaged by the restoring rod 11 and it is also provided with a pin 19 adapted to engage a slot 23 in a segment gear 20 loosely mounted on a cross shaft 21, the gear being constantly under tension of a spring 22^a secured at its other end to a fixed point in the machine so that the rear edge of the slot 23 is in constant engagement with the pin 19.

The upper edge of the gear 20 is provided with teeth 24 adapted to mesh with the teeth 25 of a pinion 26 secured to or made integral with a numeral wheel 27 on the periphery of which the proper integers are displayed in the usual manner.

It will be understood that there is one control bar, one segment gear and one numeral wheel for each denominational series.

All of the numeral wheels are loosely mounted to rotate on a common shaft 28 which is supported in suitable bearings and which bearings are adapted to be raised and lowered, in unison with the operation of the parts of the mechanism, by appropriate means indicated at 29 which is not otherwise shown in this application as it forms no part of the present invention.

Fixedly mounted above each numeral wheel is a detent 30 provided with depending teeth 31, adapted to be engaged by the teeth 25 of the numeral wheel pinion when the numeral wheel system is raised.

It will be understood that the key board system adapted to co-operate with the described mechanism is the one common in the Wales machine and described, for instance, in the patents above mentioned.

In Fig. 1, the numeral wheel 27 shown is the units wheel and the segment gear 20 co-operating therewith is the units gear, and is broken away to show the tens segment gear 20^a behind it. 10 is the units arm and is broken away to show the tens arm 10^a behind it. 17 is the units control bar and is broken away to show the tens control bar 17^a behind it.

Secured to or made integral with each numeral wheel 27 is a cross rib or trip 35 (Fig. 6), the outer tips 350 of which are coincident with the periphery of the wheel.

In the plane of each of the ribs 35 is a cam 36 (Fig. 4) provided with a vertically arranged upwardly extending member 37 slotted at 38 and 39 to engage cross rods 40 and 41 arranged across the frame 1 and which rods keep it in vertical adjustment. It is also provided with a sloping cam surface 42, a step shoulder 43 and an edge 44 having a recess 45 forming a stop 46 (see Fig. 4). A spring 47 secured to the cam and to the rod 40 serves to retract the cam to position after actuation. Pivoted to the cam 36 at 48 is a latch lever 49 having a rounded tip 50 (see Fig. 5) at its lower extremity and a slight convexity 51 at its upper extremity to engage the bar 40, against which a spring 52 is adapted to move it.

Mounted to oscillate on the restoring rod 11 and in a plane midway between the planes of the adjacent units and tens numeral wheels, is a carrying elbow lever 53^a slotted at 54, to engage a pin 55 projecting from the arm 10^a, the elbow lever having an upper pin 56 adapted to engage the cam surface 42 of the cam 36 and a lower pin 57 adapted to engage the tens segment gear 20^a. Undue movement of the lever 53^a is prevented by the pin 55.

The parts of the machine are normally in the positions shown in full line in Fig. 1, the positions of some of the parts at the end 45 of the forward stroke of the main shaft being indicated in dotted outlines. When an item is enumerated on the key board, the depressed keys serve to move the corresponding key stops, one of which is indicated at 50 32, to their effective positions.

The main shaft 2 is then oscillated toward the operator, who stands at the front of the machine. This rocks the crank 5, the roller 6 and, through the latter, the lever 8 which, in turn, rocks the shaft 9 and swings the bar 11 forward. The draft spring 15 thus stretched, oscillates the elbow 13 and advances the control bar 17 until it contacts with the stop 32 and its further forward movement ceases. The further movement of the bar 11, if any takes place, merely stretches the spring 15 without affecting the position of the control bar 17.

Simultaneously with the forward movement of the control bar 17, its pin 19, in

moving forward, has permitted the segment gear 20 to rotate on the shaft 21 under tension of the spring 22, the extent of its movement being governed by that of the control bar 17 and determined by the particular key 70 which has been depressed to set the stop 32.

The main shaft is now at the extreme end of its forward stroke and the crank 5 and lever 8 are in the positions indicated in dotted outline in Fig. 2. In the meantime, by 75 the appropriate mechanism 29 (above referred to but not described), the numeral shaft 28 has been lowered and all of the numeral wheel pinions 26 are in mesh with their respective segments 20, as shown in 80 Fig. 2, and have been moved out of engagement with their respective detents 30.

On the reverse stroke of the main shaft, the lever 8 is rocked backwardly to press the restoring rod 11 against the edges of the 85 projections 18 on the bars 17, as shown in Fig. 2, to simultaneously move the bars 17 rearwardly. In such movement, the pins 19 cause the segment gears to rotate on the shaft 21 and in so doing, rotate the numeral 90 wheel pinions 26, thus rotating the numeral wheels to accumulate the items set up by the keys, and stretching springs 22 to store them with energy for use during the next accumulating operation.

The detents 30 serve to lock the numeral wheels when the latter are in their normal positions disengaged from the segment gears and the teeth on the segment gears 20 serve a similar purpose when the numeral 100 wheel shaft is lowered, therefore, any tendency of the numeral wheels to over rotate is reduced.

When a new item is enumerated on the key board, the cycle of operations above referred 105 to is repeated, but if the second item enumerated on any wheel brings the sum of two items beyond 9, it is necessary to carry the tens digit to the wheel of next higher order.

How this is done will now be described: 110

It will be understood that two series of digits from 1 to 0 through 9 are displayed on the periphery of each numeral wheel.

Assuming that the units numeral wheel has been moved to the 9th position so that 115 if moved one tooth farther it should carry the tens digit to the tens wheel, such units wheel will be in the position shown in Fig. 2. When this wheel, in the enumeration of another item, is rotated in the direction indicated by the arrow, the rib 35 will be moved to contact with the shoulder 43 and will move the cam 36 vertically downward (the slots 38 and 39 and bars 40 and 41 serving to guide such movement) until the latch 125 lever 49 has been carried down far enough for its convex surface 41 to be pulled over by the spring 52 to engage the bar 40 (see Fig. 2) to hold the cam 36 in its lowest position where its surface 42 is in effective po- 130

sition to be engaged by the pin 56 of the carrying lever 53^a. In other words, the rotation of the units wheel has set the units cam 36 into an operative position, as shown in Fig. 2, and has itself been rotated to indicate the part of the item added in excess of 10.

The carrying lever proper 53^a is mounted on the restoring bar 11 and when this bar, in the operation of the machine, during the rearward stroke of the main shaft, is moved sufficiently, as shown in Fig. 3, the pin 56 on the carrying lever is brought into contact with the sloping surface 42 of the cam 36, and, as the lever 53^a is itself free to rotate on the bar 11, the continued movement of the bar 11 brings the pin 57 against the segment gear 20^a and moves the latter one tooth, the parts being timed and positioned to accomplish a movement of this extent and no more. In order to insure greater accuracy, however, the slot 23^a is made of such length that a further movement of the segment gear is prevented by the pin 19^a. There must be a relative movement between the segment gear 20^a and the control bar 17^a during the carrying operation and the elbow lever 13^a must remain idle during such operation in order not to actuate the printing mechanism.

Practically simultaneously with the carrying operation, and at the end of the return stroke of the main shaft, the rear edge 100^a of the arm 10^a strikes the tip 50 of the latch lever 49, to oscillate the latter on its pivot 48 against the tension of the spring 52 and disengage the surface 51 from the bar 40 to allow the cam 36 to move upward to its normal position under the influence of its spring 47.

It sometimes occurs in the usual operation of the machine that the restoring bar 11 is very near to the segment gear 20^a when the carrying operation takes place. The slope 45 of the surface 42 in the cam 36 is provided to meet such condition and to insure the proper rotation of the carrying lever 53^a even when the pin 56 and surface 42 are practically in contact when the cam 36 begins to move.

When the machine is to be "cleared" or the numeral wheels restored to zero, the numeral wheel shaft is lowered through the appropriate mechanism provided for that purpose, to cause the numeral wheel pinions to engage with their respective segment gears. How this occurs is immaterial to the present invention, but when it has occurred, and the main shaft is oscillated, the control bars 17 rock the segment gears and cause all of the wheels 27 to be rotated backward. As their respective ribs 35 are rotated, the tips 350 of these ribs are brought underneath and against the stops 46 and their further movement is prevented. This position corre-

sponds nearly to the "0" position of each wheel and the wheels remain at such position even if such forward stroke is not completed, because the further forward oscillation of the bar 11 is accommodated by the stretching of the draft springs 15. At the actual termination of the forward stroke, the numeral wheel shaft is lifted to disengage the pinions 26 from the gears 20 and the wheels are positioned at "0" and are locked in that position by the detents 30.

What we claim as new is:—

1. A wheel of lower order, a wheel of higher order, means for rotating both wheels, a vibrating arm, an oscillating lever pivoted thereon; and means for tilting the lever to engage the means whereby the wheel of higher order is rotated.

2. A wheel of lower order, a wheel of higher order, means for rotating both wheels, a vibrating arm, an oscillating lever pivoted thereon; and means adapted to be moved when the wheel of lower order is rotated, for tilting the lever to engage the means whereby the wheel of higher order is rotated.

3. In a calculating machine, the combination with a main shaft; a series of numeral wheels; and means to rotate the numeral wheels; of a vibratory arm driven from the main shaft; an oscillatory lever pivoted on the arm; and means contacted by the lever when the latter is traveling in one direction, to shift the lever to cause it to positively actuate the wheel-rotating means. 100

4. In a calculating machine, the combination with a main shaft; a series of numeral wheels; and means to rotate the numeral wheels; of a vibratory arm driven from the main shaft; an oscillatory lever pivoted on the arm; means contacted by the lever when the latter is traveling in one direction, to shift the lever to cause it to positively actuate the wheel-rotating means; and a lock to hold the lever-shifting means in effective 110 position to cause the operation of the lever.

5. A tens carrying device comprising a series of denominational wheels; means to rotate the numeral wheels; a vibratory arm; a lever pivoted on the arm, and normally 115 ineffective to actuate the wheel-rotating means; and means to increase the effective length of the lever, including a device interposed in the path of the lever, to tilt the lever and cause it to positively actuate the 120 wheel-rotating means of a wheel of higher denomination.

6. A counter of lower order; a counter of higher order; means to rotate the respective counters; a vibrating arm; an oscillatory 125 lever pivoted thereon; and means adapted to be interposed in the path of one arm of the lever to swing another arm of the lever into contact with the means which rotates the counter of higher order to force the latter 130

- to turn such counter as the vibrating lever approaches one limit of its travel.
7. A counter of lower order; a counter of higher order; means to turn the respective counters; a vibratory arm; an oscillatory lever pivoted thereto; and means adapted to be interposed in the path of the oscillatory lever to cause the latter to actuate the means which turns the counter of higher order, to turn such counter a predetermined distance as the vibratory lever approaches one limit of its travel.
8. In a calculating machine, the combination with denominational counting wheels; means to rotate said wheels; a vibratory arm; an oscillatory lever pivoted thereon; means actuated by a wheel of lower order, to cause the lever to tilt and actuate the rotating means for the wheel of next higher order, to turn said higher order wheel; and means to limit the rotation imparted at that time to said wheel.
9. A counter of lower order; a counter of higher order; means to turn the respective counters; a vibratory arm; an oscillatory lever pivoted thereto; and means actuated by the counter of lower order at one point in its rotation, said last-named means adapted to be interposed in the path of the oscillatory lever to cause the latter to actuate the means which turns the counter of higher order, to turn such counter a predetermined distance as the vibratory lever approaches one limit of its travel.
10. In a machine of the character described, a main shaft; a vibrating arm driven therefrom; an oscillatory lever pivoted on the arm; a counter; means to turn the counter; and means adapted to be interposed at predetermined times, in the path of the oscillatory lever to cause the latter to actuate the counter-rotating means and turn the counter one step.
11. In a carrying mechanism, the combination with a series of numeral wheels; and gears to turn the wheels; of means to control the advance of the gears; and having loose connections therewith; means to normally prevent relative movement between the corresponding gears and control means; means to restore the gears to normal position; normally idle carrying levers on the gear-restoring means to shift the gears relatively to their controlling means; means shifted by the numeral wheels to render said levers effective; and a lock to hold said last-named means in adjusted position.
12. In a calculating machine, the combination with a main drive shaft; of a series of denominational numeral wheels; means to rotate the wheels to directly accumulate amounts thereon and to return the wheels to zero; normally idle carrying levers shiftable bodily with the main shaft; and means interposed in the paths of the carrying le-

vers by the numeral wheels of lower orders, to rock the levers and cause them to actuate the wheel-rotating means co-acting with the wheels of next higher orders to turn the latter.

13. In a carrying mechanism, the combination with a series of numeral wheels; and gears to turn the wheels; of means to control the advance of the gears; and having loose connections therewith; means to normally prevent relative movement between the corresponding gears and control means; means to restore the gears to normal position; normally idle carrying levers on the gear-restoring means to shift the gears relatively to their controlling means; and means shifted by the numeral wheels to render said levers effective.

14. In a carrying mechanism, the combination with a series of numeral wheels; and gears to turn the wheels; of means to control the advance of the gears; and having loose connections therewith; means to normally prevent relative movement between the corresponding gears and control means; means to restore the gears to normal position; normally idle carrying levers on the gear-restoring means to shift the gears relatively to their controlling means; means shifted by the numeral wheels to render said levers effective.

15. In a carrying mechanism, the combination with a series of numeral wheels; and gears to turn the wheels; of means to control the advance of the gears; and having loose connections therewith; means to normally prevent relative movement between the corresponding gears and control means; means to restore the gears to normal position; normally idle carrying levers on the gear-restoring means to shift the gears relatively to their controlling means; means shifted by the numeral wheels to render said levers effective; and a lock to hold said last-named means in adjusted position.

16. In a calculating machine, the combination with a main shaft; a series of denominational numeral wheels; means to rotate the numeral wheels; and a vibratory arm driven from the main shaft; of a normally idle oscillatory lever pivotally mounted on the arm; and means actuated by a wheel of lower order and interposed in the path of one arm of the oscillatory lever which strikes the interposed means and is thereby turned on its pivot, as the arm continues its travel, to contact another arm with the numeral wheel-rotating means of next higher order and positively force the latter in one direction to turn its wheel.

17. A wheel of lower order; a wheel of higher order; means for rotating both

wheels; a vibrating arm; an oscillating lever pivoted thereon; and means for tilting the lever to engage the means, whereby the wheel of higher order is rotated, comprising a device on the wheel of lower order and moving with it; and a slideable stop adapted to be moved into the path of the oscillating lever by said device.

18. In a machine of the character described, a main shaft, a vibrating arm moved therefrom, an oscillating lever pivoted on the arm, a numeral wheel, means for rotating it one space; and means actuated by a wheel of lower order and interposed in the path of the oscillating lever to shift it to engage the wheel-rotating means, and including a cam intermediate the wheel of lower order, and the oscillating lever.

19. A numeral wheel of lower order, a numeral wheel of higher order, means for rotating the former past the tens position; and means for transferring the tens to the wheel of higher order by moving the latter one point, comprising a rocking arm, a carrying lever pivoted thereon, a gear adapted to mesh with the wheel of higher order, a cam normally out of the path of the carrying lever; and means on the wheel of lower order adapted to move the cam into such path.

20. In a registering machine, the combination with pinions and gears adapted for engagement and disengagement; of means operable upon the gears to effect a carrying operation, said means also effective to arrest the pinions at a predetermined point.

21. A numeral wheel and means for rotating it; a vibrating arm; a lever thereon; a cam adapted to be moved into the path of the latter; and a device on the wheel adapted to move the cam at one part of the rotation of the wheel and to be stopped by the cam at another part of said rotation.

22. In a registering machine, the combination with pinions and gears adapted for engagement and disengagement; and numeral wheels and trips turning with the pinions; of drive members for the gears; loose connections between the corresponding drive members and gears; means to prevent accidental relative movement between the corresponding gears and drive members; normally idle carrying levers; and means set by the trips to render the carrying levers effective, said means also operative to arrest the numeral wheels at zero.

23. In a register, the combination with numeral wheels; trips turning therewith; gears to turn the wheels; and means to control the excursions of the gears; of normally-idle carrying levers adapted for both pivotal and bodily movement; stops interposed by the trips, when rotated in one direction, in the paths of the carrying levers

to rock them to effective position; and shoulders on the stops contacted by the trips when rotated in the reverse direction, to arrest the numeral wheels at zero.

24. A wheel of lower order, a wheel of higher order, means for rotating both wheels; a vibrating arm; an oscillating lever pivoted thereon; and means for tilting the lever to engage the means whereby the wheel of higher order is rotated, comprising a device on the wheel of lower order and moving with it, and a slideable stop adapted to be moved into the path of the oscillating lever by said device, in combination with a latch for holding the stop in adjusted position.

25. In a calculating machine, the combination with a drive shaft; a series of denominational numeral wheels; toothed members to turn the wheels; and means to control the excursions of the toothed members; of normally idle carrying levers; means shiftable at each operation of the drive shaft, and on which the levers are pivoted; stops adjusted by the numeral wheels into the paths of the carrying levers to cause them to rock and thereby drive the toothed members to turn the wheels to effect transfers from lower to higher orders; and means to lock the stops where adjusted until the transfer operation is effected.

26. A wheel of lower order; a wheel of higher order, means for rotating both wheels; a vibrating arm; an oscillating lever pivoted thereon; and means for tilting the lever to engage the means whereby the wheel of higher order is rotated, comprising a device on the wheel of lower order and moving with it, a slideable stop adapted to be moved into the path of the oscillation lever by contact with said device; a latch for holding the stop in adjusted position; and means for disengaging the latch after it has engaged the oscillating lever.

27. In a carrying mechanism, the combination with numeral wheels; toothed members to turn the wheels; and means to control the excursions of the toothed members; of normally idle carrying levers adapted for both bodily and pivotal movements; stops adjusted by the numeral wheels into the paths of the carrying levers to cause them to rock to effective position; means to lock the stops in adjusted position until the carrying operation is effected; and lock-releasing means operative subsequently to the completion of the carry.

28. A cam adapted to be moved to one of two positions, a fixed catch; a latch lever adapted to hold the cam in one position by its engagement with the fixed catch; and means, including a numeral wheel, adapted to bring about such engagement.

29. In a calculating machine, the combination with a series of numeral wheels; and

means to rotate the wheels; of a cam; guide members therefor; numeral wheel-controlled means to adjust the cam to effective position; means to hold the cam where adjusted; 5 shiftable means, into the path of which the cam is adjusted, and operable upon the numeral wheel-rotating means to effect a carry from a wheel of lower order to that of next higher order; and means to return the cam to normal position.

30. In a calculating machine, the combination with a series of numeral wheels; and means to rotate the wheels; of a cam; numeral wheel-controlled means to adjust the cam to effective position; means to hold the cam where adjusted; shiftable means, into the path of which the cam is adjusted, and operable upon the numeral wheel-rotating means to effect a carry from a wheel of lower order to that of next higher order; and means to return the same to normal position.

31. In a calculating machine, the combination with a series of denominational numeral wheels; and means to rotate the wheels; of an adjustable cam; guide members therefor; numeral wheel-controlled means to adjust the cam to one of its positions; means to hold the cam where adjusted, including a latch lever adapted to engage one of the guide members; shiftable means into the path of which the cam is adjusted, and operable upon the numeral wheel-rotating means to effect a carry from a wheel of lower order to one of the next higher order; and means to restore the cam to normal position.

32. In a calculating machine, the combination with a series of denominational numeral wheels; and means to rotate the wheels; of an adjustable cam; guide members therefor; numeral wheel-controlled means to adjust the cam to one of its positions; means to hold the cam where adjusted, including a latch lever adapted to engage one of the guide members; shiftable means into the path of which the cam is adjusted and operable upon the numeral wheel-rotating means to effect a carry from a wheel of lower order to one of the next higher order; means to disengage the latch and guide; and means to restore the cam to normal position.

33. In a calculating machine, the combination with a series of denominational numeral wheels; and means to rotate the wheels; of an adjustable cam; guide members therefor; numeral wheel-controlled means to adjust the cam to one of its positions; means to hold the cam where adjusted, including a latch lever; a catch; and a spring to engage the latch lever with the catch; shiftable means into the path of which the cam is adjusted, and operable upon the numeral wheel-rotating means to effect a carry from

a wheel of lower order to a wheel of next higher order; and means to restore the cam to normal position.

34. In a calculating machine, the combination with a series of denominational wheels; 70 and means to rotate the wheels; of a tilttable lever operable upon the numeral wheel-rotating means to effect a carry from a wheel of lower order to a wheel of next higher order; a cam adapted to be adjusted into the path of the tilttable lever to render it operative; a fixed catch; a latch adapted to engage the catch to retain the tilttable lever where adjusted; and numeral wheel-controlled means to position the 80 latch for engagement with the catch.

35. In a calculating machine, the combination with a series of denominational numeral wheels; and means to rotate the wheels; of a vertically slidable cam; a spring 35 adapted to shift it in one direction; a fixed catch; a latch mounted on the cam and adapted to engage the catch; numeral wheel-controlled means to adjust the cam against the tension of its spring to a position in 90 which the latch will engage the catch; shiftable means rendered operative by contact with the cam when in adjusted position, to actuate the numeral wheel-rotating means and effect a carry from a wheel of lower 95 order to a wheel of next higher order; and means to enable the restoration of the parts to normal position.

36. In a calculating machine, the combination with a series of denominational numeral wheels; and means to rotate the wheels; of an adjustable cam; a catch; a latch adapted to engage the catch to hold the cam in adjusted position; numeral wheel-controlled means to adjust the cam; 100 shiftable means rendered operative by contact with the cam when in adjusted position, to actuate the numeral-wheel-rotating means and effect a carry from a wheel of lower order to one of next higher order; and 110 means to automatically disengage the latch and catch to permit the restoration of the cam.

37. In a calculating machine, the combination with a series of denominational numeral wheels; and means to rotate the wheels; of an adjustable cam; numeral wheel-controlled means to adjust the cam to one of its positions; means to hold the cam where adjusted, including a catch; and 115 a latch adapted to engage the catch; shiftable means rendered effective by contact with the cam when in adjusted position, to actuate the numeral wheel-rotating means and effect a carry from a wheel of lower 120 order to one of next higher order; and means to disengage the latch and catch, comprising a moving part of the machine.

38. In a machine of the character described, having a main shaft, the combination of a 130

fixed catch; a cam adapted to be moved to one of two positions, a latch lever adapted to hold the cam in one position by its engagement with the fixed catch, means including a numeral wheel adapted to bring about such engagement; and independent means for breaking such engagement, comprising an arm adapted to move in unison with the vibration of the main shaft of the

10 machine.

39. In a registering machine, the combination with a main drive shaft; and pinions and gears adapted for engagement and disengagement; of drive members for the gears
15 loose connections between the corresponding gears and drive members; restraining means tending to prevent relative movement between the corresponding gears and drive members; a restoring means for the drive members; normally idle carrying levers to

operate said gears irrespective of the restraining means; means controlled by the pinions and interposed in the paths of the carrying levers to render them operative during the engagement of the pinions and 25 gears; locks to hold the last named means in effective position; said restoring means adapted to release the locks subsequently to the operation of the carrying levers and to the disengagement of the pinions and gears, 30 to enable the restraining means to restore the gears to their normal positions relatively to the drive members.

Signed this 24th day of June, 1913.

JOHN P. HUNTER.
HENRY KUENTZLER.

In the presence of—
